BINDING TAPE APPLICATOR

Charles F. McBride and Homer G. Kreps,
Sturgis, Mich.

Application May 12, 1949, Serial No. 92,854

9 Claims. (Cl. 216—20)

1

This invention relates to a binding tape applicator and more particularly to a device for applying a binding tape along the cut edge of a carpet backing.

It is an object of the invention to provide a device which is of simple construction and which may be manipulated in a simple manner to apply a binding tape along the edge of carpeting, adhesive material being applied to the tape or to the carpet backing so that the tape applied by the device will adhere firmly to the carpet backing without stitching.

More specifically, the invention contemplates a device which is constructed to apply a binding tape to a carpet backing such that the tape along one of its edge portions is rolled upwardly around the cut edge of the backing material with the extreme edge of the tape imbedded in and lying along the line between the carpet backing and pile. The device is constructed such that the binding tape applied thereby prevents unravelling of the backing or pile of the carpet and at the same time presents a neat appearance along the edge of the rug.

Other objects in the way of improvements in the construction of the device and its operation will become apparent from the following specification and drawings in which:

Figure 1 is a side elevation of the device partly in section.

Figure 2 is a bottom view of the device.

Figure 3 is a partial perspective view of the bottom and rear end of the device with the tape removed.

Figure 4 is a sectional view taken along the line 4—4 in Figure 1.

Figure 5 is a sectional view taken along the line 5—5 in Figure 1 and showing the manner in which the tape is held in position on the bottom guide plate when the device is ready for use.

Figure 6 is a view corresponding to Figure 5 showing the manner in which the binding tape is applied along the edge of a carpet backing.

Referring to the drawings, and particularly to Figure 1, the tape applicator of this invention is shown comprising a base member 10 having a pair of upright arms 12 at the forward end thereof between which is supported a roll 14 of binding tape 15. Arms 12 are mounted on base 10 by means of screws 16 and are provided at their upper ends with a plurality of vertically spaced and horizontally aligned apertures 18 for accommodating rolls of binding tape of different sizes. The binding tape is preferably wound on a spool 20 which is supported between arms 12

2

by means of a pin 22 which is arranged to extend through a corresponding pair of the apertures 18.

Base 10 is preferably of rectangular shape and is horizontally slotted transversely through its mid portion as at 24 so that the upper portion of the base serves as a handle 26 for the device. The front face of base 10 is vertically slotted so as to provide a recessed guide 28 for guiding the tape from roll 14 downwardly and along the bottom face 30 of base 10. At its lower end guide 28 is fashioned with a rounded corner 32 around which the tape is pulled when the device is manipulated along the edge of a carpet.

On the bottom face 30 of base 10 there is mounted a shoe or guide plate 34. Plate 34 is arranged to be adjustably fixed on base 10 by means of screws 36 which extend through transverse slots 38 in plate 34 and thread into base 10. Slots 38 allow for the shifting of plate 34 in a transverse direction so as to accommodate the device for tapes of different widths. Plate 34 is mounted on face 30 so that the exposed face 40 of the plate is spaced below the bottom face of base 10 and so that the front edge 42 of the plate extends transversely of the tape and is spaced rearwardly of the rounded corner portion 32 of guide 28. Along one edge plate 34 is bent downwardly to provide a depending flange 44. At its front end flange 44 is bent outwardly as at 48. The mid portion 50 of flange 44 extends downwardly substantially perpendicular to the face 40 of plate 34. In effect, flange 40 forms an angle of over 90° at the front of plate 34 which gradually increases to 90° at the portion 50 and which then turns gradually inwardly to an angle of less than 90° at the portion 48. Flange 44 is shaped in this manner so as to roll or fold the tape around the cut edge 52 of a carpet backing 54. The perpendicular flange portion 50 extends along a substantial portion of the plate and serves as a guide when the device is pushed along the edge of a carpet.

For the purpose of temporarily holding tape 15 in position on plate 34 a spring 56 is provided. Spring 56 is fashioned with a short arm 58 which is adapted to be inserted within an aperture on the rear face of base 10 and with a relatively long arm 60 which, when arm 58 is engaged with base 10, is adapted to extend along and yieldably engage the inner face of plate 34 at the base of flange 44.

Although the device may be used for applying binding tape on a carpet backing on the surface of which an adhesive material is applied prior to the application of the tape, it is preferred to apply the adhesive material to the tape as it is unrolled

from roll 14. Accordingly, a bracket 62 is mounted as by screws 64 across the front end of base 10 so as to span guide recess 28. Bracket 62 supports a container 66 the side edges of which are shaped to provide supports for an adhesive applicator roll 68. Container 66 is arranged such that the outer surface of tape 15 contacts the cylindrical surface of roller 68 and causes the roller to rotate and dip in the bath of adhesive 70 within the container. The adhesive employed is preferably aqueous dispersion of latex. Roller 68 also serves to guide the tape 15 downwardly into guide portion 28 in the front face of base 10.

When it is desired to employ the device for applying a binding tape to a carpet backing, the roll of tape is arranged between arms 12 as shown in Figure 1 and a portion of the tape is unwound from roll 14 and threaded over roller 68 downwardly through guide 28 and along plate 34 with the edge of the tape substantially aligned with the lower edge of flange 44. The tape is temporarily held in this aligned position by engaging the shorter leg 58 of spring 56 in the hole on the rear face of base 10 and springing the other leg 60 from the dotted line position shown in Figure 2 to the position shown in solid lines where it resiliently engages the tape and holds the edge portion thereof against the inner face of flange 44 along the inwardly bent portion 48 of the flange. The device is then gripped by the handle portion 26 and pressed against the carpet backing with the portion 50 of flange 44 and the tape lying against the flange snugly embracing the cut edge of the carpet. While applying a downward pressure on base 10 to adhere the tape on the outer surface of backing material spring 56 is disengaged from base 10 and withdrawn in a direction longitudinally and rearwardly from engagement with the inwardly bent flange portion 48.

The device is then pushed forwardly along the edge of the carpet while a downward pressure is exerted. Since the tape adheres to the carpet backing it is obvious that as base 10 is pushed forwardly the tape 15 is progressively unwound from roll 14 and coated with latex on the outer face thereof by means of roll 68. As the tape unwinds it is guided downwardly by roll 68 and guide 28 around the curved corner portion 32 to the plate 34. As the plate 34 advances over the tape it presses the tape against the flat surface of the carpet backing 54 and causes the tape to be firmly adhered thereto. At the same time the edge portion of the tape is turned gradually upwardly by the outwardly bent flange portion 46 and is pressed against the cut edge of the backing so as to firmly adhere thereto by the perpendicular flange portion 50. The inwardly bent flange portion 48 then serves to roll the edge portion of the tape around the cut edge of the backing material and into the base of the pile material 70 along the edge of the carpet as is best shown in Figure 6.

It will thus be seen that we have provided a very simply constructed device which is admirably suited for applying a binding tape along the cut edge of a carpet backing. The device is operable in a very simple manner and serves to adhere the binding tape to the face and cut edge of the backing material very firmly. The efficacy of this operation and the neat appearance of the binding resulting therefrom are to a great extent attributable to the reverse bend along flange 44 and the positioning of plate 34. By shaping flange 44 into the configuration described

it will be appreciated that the edge portion of the tape is constructed to envelope and become firmly adhered to the cut edge of the carpet backing.

It will also be observed that by forming the plate 34 as a separate member and adjustably mounting it on the bottom face of base 10 the plate not only enables use of the device with tapes of varying widths but also concentrates the pressure applied to the device to the desired localized portion of the tape so that in effect the pressure applied to the handle portion 26 is substantially entirely utilized for the purpose of pressing the tape against the carpet backing. We have also found that the provision of the recessed guide 28 at the front end of the base together with the curved corner portion 32 greatly facilitates the ease with which the tape can be stripped from the roll and applied to the carpet.

20. What we claim is:

1. A device for manually applying a binding tape to a carpet backing around the edge of the carpet comprising a base having a substantially flat bottom face, means on the base for supporting a roll of binding tape above the base, said base at its front end having a guide member extending downwardly and in an arcuate path to said bottom face and a substantially flat plate member on said bottom face extending longitudinally of said base and having its lower face spaced below the plane of the bottom face of said base, said plate being mounted on said base with its front edge spaced rearwardly from said guide means and having a depending flange along a longitudinal edge thereof, said flange forming an obtuse angle with the plate at the forward end thereof and an acute angle at the rear end thereof and having a depth corresponding to the thickness of said carpet backing, the portion of said flange between said ends being straight and of substantial length and depending perpendicularly from said base.

2. A device for manually applying a binding tape to a carpet backing around the edge of the carpet comprising a base having a substantially flat bottom face, means on the base for supporting a roll of binding tape above the base, said base at its front end having a guide member extending downwardly and in an arcuate path to said bottom face and a substantially flat plate member on said bottom face extending longitudinally of said base and having its lower face spaced below the plane of the bottom face of said base, said plate being mounted on said base with its front edge spaced rearwardly from said guide means and having a depending flange along a longitudinal edge thereof, said flange forming an obtuse angle with the plate at the forward end thereof and an acute angle at the rear end thereof, said flange having a depth corresponding to the thickness of said carpet backing and a resilient member mounted on said base for temporarily holding the tape on said plate and against said flange, said resilient member extending forwardly from the rear edge of said plate and yieldably engaging the inner face of said flange.

3. The combination as set forth in claim 2 including adhesive applying means mounted on said base above said guide member at the forward end of said base, said adhesive applying means being arranged to contact the outer exposed surface of said tape as it is unwound from said roll and guide the tape into said guide member, said

guide member being arranged to engage said tape on the inner face thereof.

4. The combination as set forth in claim 2 including holding means on said base detachably engaging said resilient member, said resilient member being shiftable in a direction rearwardly of the plate for disengaging said member with said flange and said holding means.

5. The combination as set forth in claim 2 wherein said resilient member comprises a spring removably mounted on said base and having a leg member extending along and yieldably engaging the inner face of said flange along the rear portion thereof, said spring member being shiftable in a rearward direction to disengage said leg from said flange.

6. A device for manually applying a binding tape to a carpet backing around the edge of the carpet comprising a base having a substantially flat bottom face, means on the base for supporting a roll of binding tape above the base, guide means adjacent one end of the base for directing the tape from said roll downwardly in an arcuate path and along said bottom face, and flange means depending from said bottom face extending longitudinally of said base, said flange means terminating at a point on said bottom face spaced longitudinally from said guide means, the end of said flange means adjacent said guide means being inclined to said bottom face in one direction and the opposite end of said flange means being inclined to said bottom face in the opposite direction, the portion of said flange means intermediate said inclined portions being straight and of substantial length to serve as a guide engageable with the edge of the carpet backing and depending substantially perpendicularly from said bottom face.

7. The combination set forth in claim 6 including a resilient member adapted to be detachably mounted on said base for temporarily holding the tape against said flange means, said resilient member being adapted to yieldably engage the inner face of said flange means.

8. A device for manually applying a binding tape to a carpet backing around the edge of the carpet comprising a base having a substantially flat bottom face, means on the base for supporting a roll of binding tape above the base, said base at its front end having a guide member ex-

tending downwardly and in an arcuate path to said bottom face and a substantially flat plate member on said bottom face extending longitudinally of said base and having its lower face spaced below the plane of the bottom face of said base, said plate being mounted on said base with its front edge spaced rearwardly from said guide means and having a depending flange along a longitudinal edge thereof, said flange forming an obtuse angle with the plate at the forward end thereof and an acute angle at the rear end thereof, and resilient means detachably mounted on said base for temporarily holding the tape against the inner face of the portion of said flange forming an acute angle to said plate.

9. A device for manually applying a binding tape to a carpet backing around the edge of the carpet backing comprising a base having a bottom face, means on said base for supporting a roll of binding tape above said bottom face, said base having at its front end a guide member for directing the binding tape from said roll downwardly to said bottom face, a substantially flat plate member on said bottom face extending longitudinally of said base, said plate member having a depending flange along a longitudinal edge thereof, said flange forming an obtuse angle with the plane of said plate member at the forward end thereof and an acute angle at the rear end thereof, said flange having a depth corresponding to the thickness of said carpet backing, and a resilient member mounted on said base for temporarily holding the tape on said plate and against said flange, said resilient member extending forwardly from the rear edge of said plate and yieldably engaging the inner face of said flange.
